UNITED STATES PATENT OFFICE

ORA F. FULLER, OF SOUTH BEND, INDIANA

ROTARY BOTTLE HOLDER AND DISPLAY RACK

Application filed March 12, 1930. Serial No. 435,228.

The present invention relates to a rotary bottle holder and display rack and has for its prime object to provide a structure which is simple, inexpensive to manufacture, easy to manipulate, compact and convenient in its arrangement of parts, strong and durable, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a front elevation of the mechanism embodying the features of my invention,

Figure 2 is a side elevation thereof,

Figure 3 is a side elevation of one of the trays,

Figure 4 is a top plan view thereof,

Figure 5 is an end elevation,

Figure 6 is a detail view of one of the sprockets, and

Figure 7 is a perspective view of a portion of one of the chains.

Referring to the drawing in detail it will be seen that the letter F denotes generally a base stand which comprises a plurality of legs 5 rising from caps 6 forming seats and having elbows 7 at their upper ends. Four way couplings 8 are anchored to the elbows 7 and have end pipe rods 9 therebetween and side pipe rods 10 therebetween. Vertical pipe rods 11 rise from the couplings 8 and have elbows 12 at their upper ends between side cross pipe rods 14.

These pipe rods 11 and 14 and the elbow coupling 12 form a pair of upright frames F disposed in spaced relationship. Between the pipe rods 11 of the frame F are disposed end cross brackets 15 on which bearings 16 are mounted. Shafts 17 are journaled in these bearings 16. On each shaft 17 there is mounted a pair of spaced sprockets 18 which are formed in their peripheries at intervals with notches 19.

Chains 20 are trained over these sprockets

18 and certain links of the chains are provided with eyes 21. A plurality of elongated trays 22 for bottles have brackets 23 at the ends thereof with outwardly disposed trunnions 24 journalled in the eyes 21 so that these trays are always disposed in upright position.

On the bottom shaft 17 at one end thereof there is mounted a drum 25. Brake band sections 26 are disposed circumjacent the drum 25 being pivotally mounted as at 27 on a bracket 28 on one of the pipe rods 11. A lever 28 is pivotally mounted as at 29 to one free end of one of the sections 26 and has an extension 30 anchored to the other section. These sections 26 at their ends have ears 31 and a spring 32 is disposed about the extension 30 between the ears 31 to hold them spaced thereby holding the band sections 26 normally in a released position.

On a cross bracket 35 between a pair of the upright pipe sections 11 there is pivotally mounted a lever 36 having an extension 37 pivotally engaged with the lever 28 so that by rocking the lever 36 the brake band 26 may be tightened about the brake drum 25 to stop the lower shaft 17 and thereby stop the mechanism or hold the mechanism against rotation.

This rotary bottle holder and display rack may be used in many ways. Thus the pocket may hold bottles of milk which are samples of patrons' milk. Each patron that delivers milk is represented by a bottle. Daily samples of milk are taken from each portion and a small portion is taken from the delivery and put in these bottles to which a preservative is added and this is done daily for a period of a week or in some instances two weeks.

When the composite sample is tested for butter fat the dairy is able to estimate the worth and value of the particular milk. This mechanism may be operated in any suitable manner. It will also be seen that the same may be used for display purposes in grocery stores and the like. The trays are removable and may be shaped to accommodate any desired goods.

It is thought that the construction, opera-

tion, utility and advantages of this invention will now be quite apparent to those skilled in this art without a more detailed description thereof.

5 The present embodiment of the invention has been disclosed in considerable detail merely for the purposes of exemplification since in actual practice it attains the features of advantage enumerated as desirable in the 10 statement of the invention and the above description.

It will be apparent that changes in the details of construction, and in the combination and arrangement of parts may be resorted 15 to without departing from the spirit or scope of the invention as hereinafter claimed or sacrificing any of its advantages.

Having thus described my invention, what I claim as new is:

20 A mechanism of the class described comprising a stand, a pair of spaced parallel frames rising from the stand, a pair of shafts, one located between and adjacent the upper portions of the frames and the other shaft 25 positioned between and adjacent the lower portion of the frame; means for journalling the shaft in the frame, sprockets having spaced notches thereon, said sprockets mounted on the shaft, endless chains having 30 eye links trained over the sprockets, trays between the chains, said trays having right angular shaped brackets secured thereon, said brackets having trunnions projecting outwardly therefrom to extend through the 35 eyes forward on the links in the chains.

In testimony whereof I affix my signature.
ORA F. FULLER.
